UNITED STATES PATENT OFFICE.

ARCHIE M. BOVIER, OF ELMIRA, NEW YORK, ASSIGNOR TO AMERICAN SALES BOOK COMPANY, LIMITED, OF TORONTO, CANADA, A CORPORATION OF THE PROVINCE OF ONTARIO, CANADA.

MANIFOLDING-BOOK.

1,293,011.

Specification of Letters Patent. Patented Feb. 4, 1919.

Application filed January 21, 1916. Serial No. 73,354.

To all whom it may concern:

Be it known that I, ARCHIE M. BOVIER, a citizen of the United States, residing at Elmira in the county of Chemung and State 5 of New York, have invented certain new and useful Improvements in Manifolding-Books, of which the following is a full, clear, and exact description, such as will enable others skilled in the art to which it appertains to 10 make and use the same.

This invention relates to manifolding devices, and with respect to its more specific features to the construction of manifolding pads, order blanks, invoices, and similar devices.

One of the objects of the invention is to provide a practical device wherewith a number of copies may be obtained with the use of a minimum amount of transfer material.

Another object of the invention is the provision of a simple device for obtaining a number of copies.

Still another object of the invention is the provision of an efficient and practical 25 structure wherein record sheets and transfer sheets are secured in pad form in a conveniently operative manner.

Other objects will be in part obvious and in part pointed out hereinafter.

The invention accordingly consists in the features of construction, combinations of elements and arrangement of parts which will be exemplified in the construction herein-after set forth, and the scope of the application of which will be indicated in the following claims.

In the accompanying drawings forming part of this specification, and wherein similar reference characters refer to similar parts throughout the several views,—

Figure 1 is a perspective view of a manifolding pad embodying the invention;

Fig. 2 is a section of Fig. 1 on the line $x-y$, Fig. 1;

Fig. 3 is a view of one of the record sheets, some of the slips being turned up to expose their under faces;

Fig. 4 is a view of one of the transfer sheets, showing both faces; and

Fig. 5 is an edge view of a portion of the pad, showing the top record sheets inter-folded with the upper transfer sheet, in position to be inscribed.

The main object of the present invention

is the convenient simultaneous production of 55 a plurality of record slips, the present disclosure being concerned with the production of four of such slips. In Fig. 1 is disclosed a plurality of record sheets 1, arranged in a pile, each of said record sheets being composed of four adjacent leaves 2, 3, 4 and 5, across the sheet, there being weakened lines 6 between adjacent leaves for the purpose of readily tearing the leaves apart. Preferably 60 also each sheet 1 is of sufficient length up and down the sheet to provide a number of series of record slips, as A, B, C, and D, weakened lines being provided between the several different slips A, B, C, and D for their 65 convenient separation, when necessary. Viewed 70 in some aspects, it will be apparent from what hereinafter appears that the occurrence of permanent indicia upon the record sheets is not required, but the rapid and convenient making of the complete records is facilitated 75 by the provision of permanent indicia on the sheets in a predetermined position. As before stated, each record sheet is composed of four leaves, and preferably permanent indicia are made on the under faces of the 80 leaves 2 and 4, and on the upper faces of the leaves 3 and 5. These indicia are all similar for the several slips A, B, C, and D with the exception that the slips horizontally across the sheet may be distinguished from adjacent 85 horizontal slips in any approved manner. The upper face of the leaf 2 is preferably blank or unprovided with indicia, whereas the upper face of the leaf 4 is, though it may be blank, preferably also provided with any 90 indicia desired.

Lying upon the topmost record sheet of the pile is a transfer sheet 7 which is coated with carbon for the purpose of transferring impressions, as will hereinafter appear. In 95 the present embodiment this transfer sheet lies over three adjacent sections, leaving the fourth section uncovered. Disposed at different depths in the pile are other transfer sheets, as 8, similar to the upper transfer sheet and similarly disposed relative to the adjacent record sheet. The record sheets and the several transfer sheets are secured together to form the pile, preferably by means which independently secure the transfer sheets in their respective positions in the pile, such means comprising binders or binding devices, as staples, some of which, as 9, 100 105

pass completely through the pile so as to secure the outermost transfer sheet thereto, while others, as 10, terminate short of the top of the unconsumed pile and may immediately overlie the transfer sheet 8 which is disposed intermediate the upper and lower surfaces of the pile. These staples may be the usual rather flexible fine staples employed in manifolding devices, the free ends 5 of the legs of the staples penetrating the pile from above and being turned or clenched beneath the bottom record sheet or a supporting strawboard base member 11, should such member be provided. By manipulation 10 of the staples as by straightening the legs the staples may be readily removed. The binders are disposed along the folding line between the leaves 2 and 3, so as not to interfere with the folding of the adjacent leaves. 15 In the use of this device, the leaf 5 of the record sheet is folded along the adjacent weakened line 6, into superposed relation to the leaf 4 and to the portion, or leaf, of the transfer sheet opposite the leaf 4. The two 20 record leaves in this superposed position with the intervening transfer leaf are then folded along the next weakened line 6 into superposed relation to the leaf 3 and to the portion of the transfer sheet opposite the leaf 3. Thereafter the leaf 2 and the transfer material lying opposite thereto is folded along the remaining weakened line 6 onto the previously folded leaves. The device is 25 now ready to receive a record and the first unused slip A of the outermost leaf 2, which is the original slip, is inscribed with the desired record. If the transfer sheet is fully coated with the transfer material, as carbon, on both faces, it will be apparent that 30 the record impression will be transferred to the similar slips A of the leaves underlying the original leaf. The inscription having been made, the leaves of the record and the transfer sheet are unfolded, and the series of 35 slips A, are torn from the remainder of the topmost record sheet, and the original and the copy slips may be torn apart for subsequent desired utilization.

Although the apparatus is capable of operating with a fully coated double face transfer sheet, it is preferred to coat only those sections which are required to convey the impression to the similarly presented faces of the several leaves when in the folded condition above referred to, as for example, the upwardly presented faces, and to this end the transfer sheet is coated in strips, the leaf of the transfer sheet opposite the leaf 2 being coated only on its upper face, as at 40 12; the one opposite the leaf 3 being coated on its under face, as at 13; and the one opposite the leaf 4 being coated on its upper face, as at 14. In this wise the transfer sheet comprises three single-coated leaves 45 respectively opposite the three adjacent

leaves of the record sheet, the coats of the leaves on one face of the transfer sheet alternating with a leaf uncoated on the other face as well as with a leaf uncoated on the same face. With a transfer sheet of the alternately coated character referred to, the impressions will be duplicated on but one face of each of the superposed leaves, in the present embodiment on those faces which are upwardly presented and therefore face the 70 same way, and thus not only will superfluous impressions be avoided, but a less amount of transfer material is required than otherwise. As the record sheets are used, the pile decreases in depth, and the staples securing the 75 outermost transfer sheet may project above the upper surface of the pile so as to incommod the writer, as well as permit slight lateral movement of the upper transfer sheet, which movement tends to enlarge the 80 openings in this transfer sheet through which the staples pass. But the next transfer sheet will have been uncovered before these features assume serious proportions, 85 whereupon the staples securing the outermost transfer sheet are removed, this transfer sheet is also removed, and subsequent recording effected with the next succeeding transfer sheet, and so on.

Thus by the above-described construction 90 are accomplished, among others, the objects hereinbefore referred to.

As many changes could be made in the above construction and many apparently 100 widely different embodiments of this invention could be made without departing from the scope thereof, it is intended that all matter contained in the above description or shown in the accompanying drawings shall be interpreted as illustrative and not in a 105 limiting sense.

It is also to be understood that the language used in the following claims is intended to cover all the generic and specific features of the invention herein described, and all statements of the scope of the invention, which, as a matter of language, might be said to fall therebetween.

Having described my invention, what I claim as new and desire to secure by Letters 115 Patent is:—

1. A pad comprising, in combination, a plurality of sheets arranged in a pile, binders passing through the pile and binding the sheets together, and other binders passing 120 part way through the pile and binding together a number of sheets less than the number bound by said first-mentioned binders.

2. A pad comprising, in combination, a plurality of sheets arranged in a pile, including transfer sheets at different depths in the pile, binders passing through the pile and binding the sheets together, and other binders passing part way through the pile 125 and binding together a number of sheets less 130

than the number bound by said first-mentioned binders.

3. A manifolding device, comprising in combination, a plurality of record sheets arranged in a pile, transfer sheets between two adjacent record sheets at different depths in the pile, said record sheets each composed of a plurality of leaves, and said transfer sheets respectively overlying three leaves and comprising single coated leaves respectively opposite the three leaves of the record sheet, the coats of the leaves on one face of the transfer sheet alternating with a leaf uncoated on the other face, said record sheets having weakened lines opposite each other transversely of the pile and staples in alignment with said weakened lines transversely of the pile, securing said sheets in the pile, some of said staples arranged to secure one of the transfer sheets independently of another, leaves of said record sheet and said transfer sheets being disposed at each side of the line of staples.
4. A pad comprising, in combination, a plurality of sheets arranged in a pile, each of said sheets being adapted to be folded to form a plurality of leaves, some of which may be superposed upon others, a set of staples binding some of said sheets together along the line on which the sheets are

adapted to be folded, and a second set of staples binding sheets which are not bound by the first mentioned set.

5. A pad comprising, in combination, a plurality of sheets arranged in a pile, each 35 of said sheets being adapted to be folded to form a plurality of leaves, some of which may be superposed upon others, transfer sheets at different depths in the pile, a set of staples binding some of said sheets and 40 transfer sheets together along the line on which the sheets are adapted to be folded, and a second set of staples binding sheets and transfer sheets which are not bound by said first set. 45

6. A pad of the character described comprising, in combination, a plurality of sheets arranged in a pile, clenched staples binding all of said sheets, other clenched staples binding some of said sheets, the clenched ends of 50 said different binding staples being accessible for manipulation into condition permitting withdrawal through the pile.

In testimony whereof I affix my signature, in the presence of two witnesses.

ARCHIE M. BOVIER.
